UNITED STATES PATENT OFFICE.

ELISHA HENRY ALVORD, OF SEATTLE, WASHINGTON TERRITORY.

SASH-FASTENER.

SPECIFICATION forming part of Letters Patent No. 349,295, dated September 21, 1886.

Application filed January 23, 1886. Serial No. 189,514. (Model.)

To all whom it may concern:

Be it known that I, ELISHA HENRY ALVORD, a citizen of the United States, of the city of Seattle, in the county of King and Territory 5 of Washington, have invented certain new and useful Improvements in Sash-Fasteners; and I do hereby declare that the following is a full, clear, and exact description thereof, which will enable those skilled in the art to make and 10 use the same, reference being had to the accompanying drawings, forming part of this specification, in which—

Figure 1 is an elevation of part of a window-casing from the inside, showing the arrangement of my improved sash-fastener with its attachment. Fig. 2 represents a vertical back view of my lock with its back plate, B, removed, showing the working parts of the lock, and the slotted escutcheon-plate C turned over 20 so as to show a rear view of it and its parts. Fig. 3 is a plan and side view of the back plate, B, of the lock. Fig. 4 is a vertical section of the lock applied to the window.

Similar letters of reference indicate corresponding parts.

My improvements pertain to that kind of sash-fasteners which is placed in the frame opposite the meeting-rails, and has two bolts, one for holding each sash, both bolts being 30 synchronously moved by a single lever; and my said invention consists in the novel construction and arrangement of a sash-fastener, in which the peculiar mechanism employed 35 operates in combination with sashes having notches or recesses, whereby both sashes at any height are prevented from further opening, but not from closing.

It consists, also, in the novel arrangement of the bolts, and of the mechanism used to operate them, so as to present a burglar-proof sash-lock, whether both the sashes or either of them be partially open for ventilation or closed.

In the drawings, A represents one of the two plates which cover my lock, and I term it 45 the "face-plate." In it are rectangular slots, (marked O O,) in which bolts D D play, and also a rectangular recess for the lever F to act through, and journal-boxes H H, so fashioned as to hold the journals E E, and having side 50 openings for the backward and forward play of the bolts through the slots O and O'.

B is the other of the two plates of my lock, and I term it the "back" plate. In it are rectangular slots, also, (marked O' O',) and upon its interior face are depressions and projections, as shown, to correspond with those of the face-plate A and the working parts over which it fits.

F is a lever, which moves up and down through the side of the lock, between the plates A and B, pivoted, as shown, upon the central screw-pin, P, as a fulcrum, and acts against and assists in operating the bolts D D.

S S are flat springs for throwing the bolts D D, and are securely retained in position, as 65 shown, at one end, between the plates A and B when the lock is closed or covered. The free end of these springs rests against the backs of the bolts upon which the springs work. The bolts D D are designedly made with the bend, 70 as shown, and are provided at one end with the journals E E. The free end of the bolts are angular, and, when pressed by the springs S S, project through the slots O O and pass into corresponding angular notches, K K, in 75 the sashes, as shown. Both sashes can thus, by my invention, at any desired height for each sash, be simultaneously locked from further opening, and yet (while the locks are on the sashes) the uppersash can be run up and stopped 80 anywhere, and the lower sash can be run down and stopped anywhere, both sashes being continually locked, (without any reference to each other) at any sash-recess along the run of either, from further opening until the lever-pressure is again applied to the bolts. This 85 is an important and valuable feature of my invention, and where it is employed upon window-frames the mere act of closing an open sash is equivalent to locking it securely.

To make my sash-fasteners a complete burglar-proof invention, the slotted escutcheon-plate C is designed by me as a means through which the lever F can be safely and effectively moved as desired by the operator without access by parties on the outside of the window. This escutcheon-plate C may be placed at any desired spot in the window-stile. It is constructed, as shown, with a concavity on one side and a convexity on the other side. When 95 correctly placed in position, its convex side is sunk into the stile, and its concave side is to- 100

ward the operator. The lever F (or the rod G, if employed, as will be hereinafter accurately explained) is carried behind the convex side of the escutcheon-plate C, wherever it may be placed, and the thumb-piece W is passed into the concavity of C and through the slot L thereof, and fixed into the lever, (or lever-rod,) as shown in the figures. For ordinary windows I attach this thumb-piece W, passing it through the slot L directly to the lever F. For high windows I connect the thumb-piece through the slot L to the rod G, which is attached in any convenient manner to the lever F, and works in a groove in the frame behind the stile, the rod G being of any suitable length. If the lever alone is employed, the concavity and slot L of the escutcheon-plate C are made circular. If the intervening rod G is used, the concavity and slot are made straight. This thumb-piece W is so attached that it can be removed from the lever or rod whenever desired.

As additional precautions against any tampering with the thumb-piece from without, (when it may be more convenient not to remove it at nights or other times,) I rivet a slide (marked N) by one end to the convex side of the escutcheon-plate C. This slide is furnished with a small projection at its free end, (marked T,) which fits into a notch in the side of the slot L, and does not there prevent the run of the thumb-piece W in the slot L. When the sashes are locked, this thumb-piece is at what I term the "upper" end of the slot L, and the notch referred to is slightly below the thumb-piece. By pressing the free end of the slide N across the slot and under the thumb-piece it completely obstructs the slot and prevents unlocking the sashes. Thus security is afforded against access to the thumb-piece from without, particularly at nights, when the sashes, both or either, may be left partly open for ventilation. I also provide for fastening the thumb-piece W at each end of the slot L in this wise: I make an offset or recess, which I term a "stop-notch," at each end of the slot L in the side of the slot. These stop-notches are marked in the figures Y and Y'. The thumb-piece W is purposely so formed that, when in its working or normal position in the lever or lever-rod, it will freely run along the slot L under the operator's hand; but when keyed around by the operator at either end of the slot, a central bulge will engage a stop-notch, Y or Y', (as the case may be,) and hold the thumb-piece there. Thus at the stop-notch Y' the thumb-piece will lock the sashes and keep them locked from further opening, but not from closing, while at the stop-notch Y it will unlock the sashes and keep them unlocked whenever found convenient so to do. When the parts of the lock are all placed together, the single screw-pin P, passed through the two plates A and B, and the lever F between them, secures all the parts of the lock together. The lock is then placed in position in

the window-frame at the meeting-rails. The pivoted lever F is operated through the slotted escutcheon-plate C wherever it is placed in the stile, and is made to move in the desired direction along the side aperture between the bolts D D and the plate A. This lever presses both bolts simultaneously, throwing them back against the springs S S, and withdrawing both bolts from the notches of the sashes, and thus unfastening both sashes.

Having thus fully described my invention, what I claim as new, and desire to secure by Letters Patent from the United States, is—

1. The combination, with the notched sashes K K, of the plate A, having slots O O, and the plate B, having slots O' O', the bolts D D, springs S S, the lever F, working upon the pin P, and having the thumb-piece W, and the escutcheon-plate C, having the slot L, substantially as described. 80
  2. The combination, with the notched sashes K K, of the slotted plates A and B, bolts D D, springs S S, pin P, and lever F, having the thumb-piece W, and the slotted escutcheon-plate C, provided with slide N, carrying projection T, and the stop-notches Y and Y', substantially as set forth. 90
  3. In sash-fasteners, the bended bolts D D, pivoted on the journals E E, between the plates A and B, and having angular ends which are operated through double slots O O and O' O' in the two plates A and B by the lever F, pivoted on P, and the springs S S, acting upon the backs of the bolts, substantially as shown. 95
  4. In combination with the slotted plates A and B, the lever F, pivoted between them and operating simultaneously the bolts D D by wedge movement between the bolts and the face-plate A, as herein substantially described. 105
  5. In combination with the slotted plates A and B, the springs S S, secured between the plates, as shown, and operating the bolts D D, each spring operating its bolt in the notches independently of the other, substantially as set forth. 110
  6. In sash-fasteners, the escutcheon-plate C, having slot L and slide N, carrying the projection T, and the stop-notches Y and Y', connected with the lever-rod G by a thumb-piece, W, which operates the lever F by operating the rod G through the slot L, substantially as indicated and set forth. 115
  7. In sash-fasteners, the escutcheon-plate C, constructed as described, connected with the lever F by the thumb-piece W, which operates the lever through the slot L, substantially as described. 120
- In testimony that I claim the foregoing I have hereto set my hand this 14th day of January, 1886, in the presence of two witnesses.

ELISHA HENRY ALVORD.
